PARALLEL MOTION PICKER STICK
MECHANISM FOR LOOMS

Harry A. Davis, Hopedale, Mass.

Application September 23, 1939, Serial No. 296,262

12 Claims. (Cl. 139—150)

This invention relates to improvements in parallel motion picker stick mechanism for looms, and the principal object thereof is to provide mechanism which will insure axial thrust of the shuttle by the picker stick in parallelism with the lay.

In usual picker stick motions the impulse given to the picker stick by the pick-motion and lug strap causes a lifting or jumping of the picker stick at the end of the stroke and also a longitudinal movement of the rocker upon the rocker stand at each actuation of the picker stick, thereby causing improper engagement of the picker stick with the shuttle during its impelling stroke which is likely to injure the shuttle and also to wear the shuttle box. By the present invention mechanism is provided for insuring accurate movement of the shuttle thereby eliminating these defects and increasing the life of the shuttle and shuttle box and avoiding the production of seconds in the cloth being woven.

In usual picker stick constructions the picker stick extends through the rocker shoe and the stand and is connected at its lower end to a strap which extends around a spring drum which maintains such tension upon the lower end of the picker stick as to return the picker stick to normal position after actuation by the pick-motion and in such construction the lower end portion of the picker stick is held in contact with an abutment, usually in the form of a wedge or roll, located within the slot in the rocker stand and the sudden impulse imparted to the picker stick causes wear upon this abutment as well as serious misalignment of parts and also produces unnecessary noise in the operation of the loom.

Another object of the invention is to provide a picker stick mechanism in which the picker stick does not extend through the rocker and rocker stand, and in which the rocker is maintained constantly seated upon its support during the entire rocking movement in both directions.

A further object of the invention is to provide a construction in which a flexible cushioning member is interposed between the rocker and rocker stand, thereby practically eliminating the noise and supplying sufficient cushioning action to absorb the abrupt impact of connecting parts on the picker stick at the time of pick and to prevent jumping of the picker which in usual constructions is produced by the jumping of the picker stick.

In usual picker stick constructions the spring drum, which is connected to the picker stick, is

mounted upon the rocker stand between the picker stick and the loom side, thereby necessitating the use of a rather lengthy strap of expensive leather connecting the spring drum to the picker stick and at the same time making less effective the hold-down effect of the spring on the rocker.

Another feature of the invention consists in providing mechanism which will permit the locating of the spring drum between the position of the picker stick and the end of the rocker stand with a relatively short connection to the adjacent end of the rocker, thus enabling the saving of expensive leather by the use of a much shorter strap and gaining the advantage of practically a direct hold-down effect on the rocker.

A further object of the invention is to provide a connection between the strap of the spring drum and the rocker in the form of a stirrup having parallel metal links located closely adjacent to the opposite sides of the rocker stand and rocker which serve to prevent lateral movement of the rocker, and also providing suitable guides for the outer end of the rocker, thereby preventing twisting movement of the picker stick and insuring the proper axial thrust of the picker stick upon the shuttle.

Another object of the invention is to provide an improved adjustable connection between the picker stick and the rocker.

These and other objects and features of the invention will more fully appear from the following description and the accompanying drawing and will be particularly pointed out in the claims.

A preferred embodiment of the invention is illustrated in the drawing, in which,

Fig. 1 is a front elevation, partly in section, of the lower left hand portion of a loom embodying the preferred form of the invention, the connection between the picker stick and rocker arm being broken away and shown in section;

Fig. 2 is a detail plan view of the construction illustrated in Fig. 1, the picker stick being shown in section;

Fig. 3 is an enlarged detail view, mainly in vertical section on line 3—3 Fig. 1; and,

Fig. 4 is an enlarged detail view of the shaft and hook for connecting the stirrup which engages the outer end of the rocker to the strap of the spring drum.

In the preferred construction illustrated the left side 1 of the loom frame is shown as supporting the usual rocker shaft upon which is mounted a stand 2 for the picker stick rocker or shoe which is provided with a preferably flat sur-

face 3 upon which the curved surface 4 of the rocker is supported. The rocker 5 is provided approximately centrally of its length with an upwardly extending hollow boss 6 having a vertical rectangular aperture therein which may extend through the shoe. The lower end of the picker stick 7 extends into this aperture and a channel-shaped metal member 8, which is interposed between the side of the picker stick and the inner vertical wall of the boss, fits upon the picker stick. The lower end of the channel-shaped member 8 is provided with a rib 9 which preferably seats in a recess in the lower end of the adjacent wall of the boss 6. The picker stick is clamped in the boss by a bolt 10 which passes through the boss 6, the central portion of the channel-shaped plate 8, and a channel-shaped keeper 11 which fits upon the opposite side of the picker stick and is provided with a nut 12 which when set up will secure the parts firmly together. An adjusting screw 13, which is mounted in the upper part of the boss 6, engages the member 8 and is provided with the usual set nut to retain it in adjusted position. By reason of this construction the picker stick may be accurately adjusted to maintain it in proper position relatively to the curvature of the surface 4 of the rocker shoe, so that the upper end of the picker stick will exert an accurate axial thrust upon the shuttle in parallelism with the lay when the picker stick is actuated by the pick mechanism.

By reason of the construction aforesaid the lower end of the picker stick does not extend through the rocker shoe and of course does not extend through the rocker stand as in usual constructions, thereby obtaining advantages which will hereinafter more fully appear.

One of the objects of the invention, as above pointed out, is to provide a parallel motion picker stick mechanism of the character described, in which the means for preventing jumping of the picker stick and longitudinal movement of the rocker is prevented comprising yielding means exerting a gradually increasing downward and inward pressure on the outer end of the rocker as it moves upwardly with means connecting the inner end of the rocker to the rocker stand acting both to resist longitudinal inward movement of the rocker relatively to the rocker stand and to apply a gradually increasing downward force to the inner end of the rocker during the upward rocking movement thereof.

In the preferred embodiment of the invention illustrated this is accomplished by providing, in a suitable position upon the rocker stand beyond the outer side of the picker stick and the extreme outer end of the rocker stand, a downwardly extending bracket 14 supporting a spring actuated drum 15 upon which is mounted a strap 16, the free end of which is connected by suitable means to the outer end of the rocker. The drum 15 desirably is provided with flanges 15x to provide a channel which will insure proper winding of the strap upon the drum. The bracket 14 is so positioned that the force applied to the outer end of the rocker acts downwardly and inwardly with respect to the adjacent loom side.

The means for preventing longitudinal movement of the rocker upon the rocker shoe, and also for preventing the lifting of the rocker shoe, comprises a flexible member 17 which is connected at its outer end by suitable means such as bolts 18 to the end of the rocker stand and preferably extends along the upper surface 3 of the rocker stand between the rocker stand and

the rocker and is connected at its inner end by suitable means, such as a bolt 19, to the upturned inner end of the rocker shoe. The flexible inextensible member 17 may be of any suitable character such as a strap of high grade leather, or of inextensible woven fabric, or a plurality of associated inextensible flexible members of any suitable form. In the latter case suitable longitudinal channels or grooves (not shown) in the under surface of the shoe may be provided.

The inner end of the shoe, which in usual constructions is provided with a longitudinal central reinforcing rib 20, desirably is provided near its end with upwardly extending side flanges 21 having flat outer surfaces adapted slidably to engage the inner faces of vertical guides 22 which may be integral with the rocker stand or in the form of a U-shaped member 23 embracing and welded, or otherwise secured to the rocker stand.

By reason of this construction the flexible member 17, whether in the form of a leather strap, an inextensible woven web of fibrous material, or other suitable construction, will form a cushion between the curved surface of the shoe and the upper surface of the rocker stand and will thereby minimize or eliminate noise which might otherwise be produced by the rocking of metal upon metal. The guides 22 prevent any lateral movement of the shoe relatively to the rocker stand.

In the preferred construction illustrated the outer end of the rocker shoe is connected to the strap 16 of the spring drum by a stirrup comprising parallel metal links 24 preferably having at their upper ends bosses which are connected by a bolt 25 which passes through a boss 26 extending upwardly from the outer end of the rocker shoe with a spacing sleeve 27 mounted on said bolt and at its ends engaging the bosses on the links 24. The links 24 are so positioned as to slidably engage the edges of the rocker stand 2 and thereby prevent lateral movement of the outer end of the rocker relatively to the rocker stand. Such guiding means in cooperation with the guides 22 effectively prevent any possible lateral twisting movement of the rocker relatively to the rocker stand.

The lower ends of the links 24 are connected by a shaft 28, preferably having reduced and screw threaded end portions which extend through lower bosses upon the lower ends of the links 24. In the preferred construction the shaft 28 has mounted in it centrally of its length a downwardly extending hook 29 adapted to engage a suitable hole or grommet in the free end of the strap 16 which is mounted on the spring drum 15.

A preferred connection between the upper ends of the links 24 and the upwardly extending boss 26 on the end of the rocker shoe is illustrated in the enlarged detail view Fig. 3 which shows the bosses at the upper end of the links 24 as provided with shallow cylindrical inward extensions 30 which will fit within complementary cylindrical countersinks 31 in the ends of the boss 26, the cylindrical extensions 30 forming journals for the upper ends of the links 24. The countersinks 31 are somewhat deeper than the cylindrical extensions 30 and the spacing sleeve 27, which abuts against the ends of the extensions 30, prevents binding of the pivotal connection when the nut on the connecting bolt 25 is set up.

The preferred form of spring drum mechanism for maintaining the tension upon the strap 16 and through the links 24 upon the outer end of the rocker is also illustrated in Fig. 3 in which

the bracket 14 is shown as integral with the rocker stand 2 and extending outwardly and downwardly therefrom. A spindle, which is mounted upon the depending bracket, comprises a cylindrical portion 32 which is mounted upon a squared shank portion 33 of a bolt 34 which is mounted in the bracket 16 and the drum 15 to which the strap 16 is attached is rotatably mounted upon this cylindrical portion. This 10 spindle also comprises an integral conoidal portion 35 which abuts against the inner face of the bracket and is provided with a toothed flange 36. A spiral spring 37 surrounds the spindle 35 and is anchored at one end in the slot 38 in the 15 conical portion of the spindle and at its other end extends into an annular recess 39 on the drum and is fixedly secured to the drum. When the strap 16 is secured to the link 24 the spindle may be rotated in the proper direction to place 20 the spring 37 under the desired degree of tension and the spindle then locked in adjusted position by suitable means such as by a locking screw 40 which is mounted in the bracket and engages a recess between adjacent teeth of the toothed 25 flange 36. The screw 40 is provided with a suitable lock nut 41 to prevent withdrawal of the screw 40 by reason of the vibration of the loom. By reason of this construction a desired tension 30 may be placed upon the strap 16 and the stirrup 24 thereby to exert a proper pressure upon the outer end of the rocker 5.

In the operation of the device the downward and inward yielding pressure exerted upon the outer end of the rocker shoe holds the rocker 35 firmly down upon the flexible member 17 and the rocker stand therebeneath and also produces resultant force toward the loom side. This longitudinal force is counterbalanced and longitudinal movement of the rocker prevented by the inextensible flexible member 17 which is attached to 40 the inner end of the rocker and to the outer end of the rocker stand. Tension imposed upon the flexible member 17, which follows the contour of the inner end of the rocker, also produces a downward 45 resultant force sufficient to hold the inner end of the rocker from being lifted by the action of the picker mechanism. The stirrup links 24 at one end of the rocker and the vertical guides 22 at the other end of the rocker prevent any lateral 50 or twisting movement of the picker stick. The construction is therefore such as to insure a proper "parallel motion" at the upper end of the picker stick which will cause it at all times properly to exert the thrust axially of the shuttle in 55 such parallelism to the lay as to avoid injury to the shuttle, the shuttle box or the lay.

It will be understood that the particular embodiments of the invention shown and described herein are of an illustrative character and not 60 restrictive of the meaning and scope of the following claims.

Having thus described the invention, what is claimed as new, and desired to be secured by Letters Patent, is:

65 1. In a parallel motion picker stick mechanism for looms having a lay rock shaft provided with a horizontal rocker stand and a picker stick having a rocker mounted on said rocker stand, means located between the outer side of said picker stick 70 and the outer end of said rocker stand for preventing jumping of said picker stick and longitudinal movement of said rocker comprising yieldable means exerting a gradually increasing downward and inward pressure on the outer end 75 of said rocker, and inextensible flexible means

connected to the inner end portion of said rocker and extending outwardly and connected to said stand and acting to prevent longitudinal inward movement of said rocker relatively to said stand and to apply gradually increasing downward force to the inner end of said rocker during the upward rocking movement thereof. 5

2. In a parallel motion picker stick mechanism for looms having a lay rock shaft provided with a horizontal rocker stand and a picker stick 10 having a rocker mounted on said rocker stand, means located between the outer side of said picker stick and the outer end of said rocker stand for preventing jumping of said picker stick and longitudinal movement of said rocker comprising yieldable means exerting a downward and inward pressure on the outer end of said rocker, and an inextensible flexible cushioning member lying between said rocker and said stand connected to the inner end of said rocker and to 15 the outer end of said stand to resist downward force at the time of pick. 20

3. In a parallel motion picker stick mechanism for looms having a lay rock shaft provided with a horizontal rocker stand and a picker stick 25 having a rocker mounted on said rocker stand, means for preventing jumping of said picker stick and longitudinal movement of said rocker located between the outer side of said picker stick and the extreme outer end of said rocker 30 stand comprising adjustably controllable yieldable means exerting a gradually increasing downward and inward pressure on the outer end of said rocker, and an inextensible flexible cushioning member lying between said rocker and said 35 stand connected to the inner end of said rocker and to the outer end of said stand, acting to resist, sustain and neutralize downward force at the time of pick.

4. In a parallel motion picker stick mechanism for looms having a lay rock shaft provided with a rocker stand, a rocker mounted on said rocker stand having a socket for a picker stick, a picker stick mounted in said socket but not extending beyond the arcuate face of said rocker, a metallic clamping member intermediate of the rear edge of said picker stick and the wall of said socket having a boss at its lower end, means for clamping the picker stick and boss against the adjacent wall of said socket, and an adjusting screw located above said clamping means, 45 yieldable means connecting the outer end of said rocker to said rocker stand exerting a downward and inward pressure on the outer end of said rocker and an inextensible strap located between 50 said rocker and said rocker stand connecting the inner end of said rocker to the outer end portion of said rocker stand. 55

5. In a parallel motion picker stick mechanism for looms having a lay rock shaft provided with a 60 rocker stand, a rocker mounted on said rocker stand, a picker stick mounted in said rocker but not extending beyond the arcuate under surface of said rocker, a peripherally channelled spring drum mounted on said rocker stand outwardly of said picker stick but inwardly of the extreme outer end of said rocker, a flexible member mounted on said drum and guided in the peripheral channel thereof, means connecting said flexible member to the outer end of said rocker and 65 flexible cushioning means lying between said rocker and said stand connecting the inner end of said rocker to the outer end portion of said stand. 70

6. In a parallel motion picker stick mechanism for looms having a lay rock shaft provided with a 75

rocker stand, a rocker mounted on said rocker stand, a picker stick mounted in said rocker and adjustably and fixedly attached to it but not extending beyond the arcuate under surface of said 5 rocker, a peripherally channeled spring drum mounted on said rocker stand beyond the outside of said picker stick and inwardly of the extreme outer end of said rocker stand, a strap mounted on said drum guided in the peripheral channel 10 thereof, means connecting said strap to the outer end of said rocker, flexible cushioning means lying between said rocker and said stand connecting the inner end of said rocker to the outer end portion of said stand, and vertical guides extending 15 upwardly from said stand upon opposite sides of and adjacent to the inner ends of said rocker for preventing lateral movement of said rocker relatively to said rocker stand.

7. In a parallel motion picker stick mechanism 20 for looms having a lay rock shaft provided with a rocker stand, a rocker mounted on said rocker stand, a picker stick mounted in said rocker but not extending beyond the arcuate under surface of said rocker, a spring drum mounted near the 25 outer end of said rocker stand but inwardly of the end of said rocker, a strap on said drum, a stirrup connecting said band to the outer end of said rocker comprising parallel links lying closely adjacent to opposite sides of said rocker and 30 pivotally connected at their upper ends to said rocker and having means pivotally connected to the lower end and detachably connected to the end of said strap.

8. In a parallel motion picker stick mechanism 35 for looms having a lay rock shaft provided with a rocker stand, a rocker mounted on said rocker stand, a picker stick mounted in said rocker but not extending beyond the arcuate under surface of said rocker, a spring drum mounted near the 40 outer end of said rocker stand but inwardly of the end of said rocker, a strap on said drum, a stirrup connecting said band to the outer end of said rocker comprising parallel links lying closely adjacent to the edges of said rocker stand and 45 rocker pivotally connected at their upper ends to said rocker and connected at their lower ends by a member having a central hook adapted detachably to engage an aperture in the end of said strap.

50 9. In a parallel motion picker stick mechanism for looms having a rocker presenting a horizontal rocker stand, a rocker mounted on said rocker stand having a socket to receive a picker stick, a picker stick mounted in said socket but not ex-

tending beyond the arcuate face of said rocker, an inextensible flexible strap secured at one end to the inner end of said rocker and at its other end to the outer end of said rocker stand, a bracket connected to said rocker stand inwardly 5 of the end of said rocker and outwardly of the position of said picker stick, a spring drum rotatably mounted in said bracket, a strap having one end secured to said drum, and means detachably secured to the other end of said strap extending upwardly and outwardly and pivotally connected to the outer end of said rocker.

10. In a parallel motion picker stick mechanism 10 for looms having a rocker presenting a horizontal rocker stand, a rocker mounted on said rocker stand having a socket to receive a picker stick, a picker stick mounted in said socket, means for returning the picker stick to normal position comprising a stirrup pivotally connected to the outer end of the rocker having parallel guiding 15 links adjacent to and slidably engaging the edges of the rocker stand, and resilient means engaging the lower end of the stirrup acting to exert a downward and inward force through said stirrup upon the outer end of the rocker arm.

11. In a parallel motion picker stick mechanism 20 for looms having a lay rock shaft provided with a horizontal rocker stand, a picker stick having a rocker mounted on the rocker stand, said rocker having upon its outer end an upwardly projecting 25 boss provided with cylindrical countersinks, a stirrup connected to said boss comprising links having cylindrical extensions mounted within the countersinks in said boss and slidably engaging the vertical sides of the rocker stand, a shaft journaled 30 in the lower ends of said links having midway of its length a downwardly extending hook, and a spring drum mounted on said rocker stand having a tension strap secured at one end thereto and provided with means at its free end to engage 35 said hook.

12. In a parallel motion picker stick mechanism 40 for looms having a lay rock shaft provided with a rocker stand, a rocker mounted on said rocker stand, a picker stick mounted in said rocker, a 45 spring drum mounted on said rocker stand provided with a channeled peripheral surface, a strap having one end secured to said drum and lying within said channel, means connecting the other end of said strap to the outer end of said 50 rocker, and flexible means lying between said rocker and stand connecting the inner end of said rocker to the outer end portion of said stand.

HARRY A. DAVIS.
